DESIGN FOR COVER PAPER OR SIMILAR ARTICLE

Thomas L. Stone, Newark, N. J., assignor to The Hinde and Dauch Paper Company, Sandusky, Ohio, a corporation of Ohio

Application May 12, 1939, Serial No. 84,945

Term of patent 14 years

To all whom it may concern:

Be it known that I, Thomas L. Stone, a citizen of the United States and a resident of Newark, Essex County, New Jersey, have invented a new, original, and ornamental Design for Cover Paper or Similar Article, of which the following is a specification, reference being had to the accompanying drawing, forming a part thereof.

In the accompanying drawing the figure is a face view of a portion of cover paper or similar article showing my new design.

The dotted lines A—B—C—D inclose a repeat unit of the design.

I claim:

The ornamental design for cover paper or similar article, as shown and described.

THOMAS L. STONE.
